UNITED STATES PATENT OFFICE.

DAVID S. CLARKE, OF DENVER, COLORADO.

TOY.

Application filed November 10, 1921. Serial No. 514,222.

To all whom it may concern:

Be it known that I, DAVID S. CLARKE, a citizen of the United States, and a resident of Denver, in the county of Denver and 5 State of Colorado, have invented a new and useful Improvement in Toys, of which the following is a full, clear, and exact description.

My invention relates to improvements in 10 toys, and it consists in the combinations, constructions and arrangements herein described and claimed.

An object of my invention is to provide a 15 toy having card-board figures, such as roosters, buffaloes, or the like, arranged to face one another and in which the figures may be caused to move to stimulate action as in a fight.

A further object of my invention is to provide 20 a toy of the character described, which is cheap to manufacture and which is not liable to break easily.

Other objects and advantages will appear 25 in the following specification, and the novel features of the invention will be particularly pointed out in the appended claims.

My invention is illustrated in the accompanying drawings, forming part of this application, in which

30 Fig. 1 is a full view of one embodiment of my invention,

Fig. 2 is a sectional view along the line 2—2 of Fig. 1.

In carrying out my invention, I make use 35 of a wire supporting member 1. The wire 1 is preferably of spring steel, but any other spring wire will serve the purpose.

The wire member 1 is provided with a loop 40 portion 2 intermediate its length substantially as shown at Fig. 1. The ends of the loop 3 and 4 are bent about one another so that pressure, as by the hand upon the loop, will cause it to contract and move the ends 3 and 4 away from one another. Substantially horizontal lengths 5 and 6 are formed 45 by the ends of the loop 2 and terminate in transverse axial portions 7 and horizontal retaining portions 8.

Card-board figures 9 and 10 representing 50 roosters, buffaloes, boars, or the like, are provided with holes 11 therethrough adjacent their feet portions. The holes 11 are arranged to receive the axial portions 7 of the wire supporting member 1. Each of the 55 figures 9 and 10 are provided with notches 12 in the lower edge of the card-board below

the holes 11. The bottom of the notches 12 are curved to conform with a radial line from the holes 11. The sides 13 and 14 of the notches constitute stops for the pivotal movement of the figures 9 and 10 upon the axial portions 7 by their engagement with the retaining portions 8, as previously described. This structure is more clearly shown in Fig. 2.

From the foregoing description of the various parts of the device, the operation thereof may be readily understood. The toy is grasped in the hand and held by the loop portion 2. A pressure of the hand upon the loop portion 2 will contract the loop in a way to cause the horizontal lengths 5 and 6 of the wire supporting member 1 to move toward one another. This will cause the figures 9 and 10 which normally are in a position with their heads down to move toward one another and in doing so simulate the appearance of an attack upon one another by the roosters, or whatever animal is represented. If now, the loop is rapidly contracted and released, the sudden releasing of the loop 2 will cause the figures 9 and 10 to move upon their axial points 11 and the head will be thrown upward and down. The movement of the figures 9 and 10 is varied by the figures striking one another and in the position in which they are held in the hand. Such variation makes the appearance 85 of the fighting more interesting.

I claim:

1. A device of the character described comprising a spring wire supporting member arranged so that the ends of said supporting member may be moved toward one another at will, transverse axial members integral with said supporting member and disposed at the ends thereof, a pair of figures or card-board or the like pivotally disposed on said axial members, said figures having stops integral therewith, and means carried by said supporting member adjacent the opposite ends thereof for engaging with said stops to limit the pivotal movement of said figures on said axial members.

2. A device of the character described comprising a spring wire supporting member, said member being formed with a loop intermediate its length and arranged so that the ends of said member are moved toward one another when said loop is manually contracted, transverse axial members integral with said supporting member and disposed

at the ends thereof, a pair of silhouette figures of firm material pivotally disposed on said axial members, said figures having stops integral therewith, and members carried by 5 said supporting member at the outer ends thereof for engaging with said stops to limit the pivotal movement of said figures on said axial members.

3. A device of the character described 10 comprising a spring wire supporting member, said member being formed with a loop intermediate its length and arranged so that the ends of said member are moved toward

one another when said loop is manually contracted, transverse axial members integral with said supporting members and disposed at the ends thereof, a pair of figures of card-board or the like pivotally disposed on said axial members, said figures having stops carried thereon, and means carried by 15 said supporting member at the outer ends thereof for engaging with said stops to limit the pivotal movement of said figures on said axial members.

DAVID S. CLARKE.
